UNITED STATES PATENT OFFICE.

CHARLES W. COLLER AND JOHN S. NAERY, OF LAFAYETTE, INDIANA.

DESIGN FOR A PLATFORM FOR CARS.

SPECIFICATION forming part of Design No. 32,546, dated April 17, 1900.

Application filed March 21, 1900. Serial No. 9,614. Term of patent 31 years.

To all whom it may concern:

Be it known that we, CHARLES W. COLLER and JOHN S. NAERY, citizens of the United States, residing at Lafayette, in the county 5 of Tippecanoe and State of Indiana, have invented and produced a new and original Design for a Platform for Cars, of which the following is a specification, reference being had to the accompanying drawings, forming 10 part thereof.

Referring to the accompanying drawings, Figure 1 is a plan view of our new and original design for platforms for cars. Fig. 2 is a side elevation thereof, the left-hand end of the 15 view being in section. Fig. 3 is an end view looking in the direction of the arrow 3, Fig. 1.

The essential features of our new and original design comprise a skeleton frame consisting, essentially, of two body-pieces arranged 20 side by side and connected by webs and having side extensions projecting outwardly therefrom, having at its front end hollow projections.

Thus referring to the drawings, A and A' 25 are the body portions, each made up of plates

a a', having cross-pieces a², and the two body portions A are joined by webs B B B. Extending laterally from the outer side of each body portion A are the projections C C, the outer portions c of which are rounded, and interposed between these portions are the body portions c' c'. Extending from the front end of the platform are the hollow projections D D. Arranged in different positions on the body portions A A' are pillars F F, the upper 30 portions f of which are rectangular in shape, while the lower portions f' are cylindrical. 35

What we claim is—

The new and original design for a platform for cars, substantially as shown and described. 40

In testimony whereof we have signed our names to this specification in the presence of two subscribing witnesses.

CHAS. W. COLLER.
JOHN S. NAERY.
